UNITED STATES PATENT OFFICE.

LUTHER F. COLE, OF SPARKS, NEVADA.

BADGE.

Application filed March 7, 1924. Serial No. 697,597.

To all whom it may concern:

Be it known that I, LUTHER F. COLE, a citizen of the United States, residing at Sparks, in the county of Washoe and State 5 of Nevada, have invented certain new and useful Improvements in a Badge, of which the following is a specification.

My present invention relates to badges or emblems, and the primary object thereof is 10 in the provision of a device of the character described, embodying features whereby different indicia or other symbols or characters which are disposed at opposite faces of the badge, may be readily exposed to view.

15 A further object of the invention is to provide a reversible badge such as may be used on railroads or for any other desirable purposes whereby a single badge may be employed for designating a change in title of 20 an employee.

A still further object of the invention is in 25 the provision of a reversible badge, embodying novel securing means which may be readily swung to either side of the badge, and being so formed as to efficiently retain 30 the badge upon the wearer when disposed at either side of the badge.

Other objects and advantages of the invention will appear in the following detailed 35 description, taken in connection with the accompanying drawing, forming a part of this specification, and in which drawing,

Figure 1 is a view of one side of the badge and showing an indicia as appearing thereon when the badge is being worn in one position.

Figure 2 is a view of the opposite side of 40 the badge as shown in Figure 1, and showing the arrangement of the securing means.

Figure 3 is a view of the opposite side from that shown in Figure 1, and showing the indicia as appearing thereon when the badge is being worn in an opposite position from that shown in Figure 1.

45 Figure 4 is a view of the opposite side from that shown in Figure 3, and showing the arrangement of the securing means.

Figure 5 is a slightly enlarged end view 50 of the badge showing by way of dotted position the manner in which the securing means may be swung into operative position at opposite sides of the badge.

55 Figure 6 is a still further enlarged central vertical section of the badge taken on the line 6—6 of Figure 4 and showing the relative position of the securing means when

disposed at the side of the badge opposite to that shown in Figure 5, and

Figure 7 is a perspective view of a keeper 60 forming a part of the securing means.

Referring to the drawing in detail, and 65 wherein similar reference characters designate corresponding parts throughout the several views, the letter A designates generally, an improved reversible badge comprising an indicia carrying portion in the form of a plate B and a securing or attaching means C, the attaching means C comprising a pin D adapted to be swung into position at either side of the plate B by means of the 70 pivot or hinge member E, and to be held in an operative position at either side of the plate by means of a retaining member or keeper F which may also be swung to opposite sides of the plate B.

75 The indicia carrying plate B which is preferably made of sheet metal, may have its marginal edges formed to any desirable shape or configuration. An indicia, which is designated by the numeral 10, is provided 80 at each side of the plate B and in the example shown, an unlike indicia has been shown at opposite sides of the plate for illustrating one manner in which the badge may be used. If desired, one side of the plate B 85 may be colored different from the opposite side for enabling an observer to more readily distinguish which indicia is being exposed to view. It can be seen therefore that by so disposing the attaching means C at one side 90 of the plate B, the indicia "Freight conductor" will be viewed and by disposing the attaching means C at the opposite side of the plate B, that the indicia "Freight brakeman" will be viewed.

95 The pin D which may be made of spring wire, is formed with a straight end portion 11, an intermediately disposed V-shaped portion 12 and a reverse curved hook portion 13 which is disposed at the opposite end 100 from said straight portion and being pointed for enabling the easy insertion of the pin D into the apparel of the wearer. The reverse curved hook portion 13 forms oppositely disposed arcuate concavities 14 and 15 which are adapted to cooperate with the keeper F for maintaining the pin D in an operative position at either side of the plate B.

110 The pivot or hinge member E which connects the pin D to the plate B and which permits of the pin D to be swung into posi-

tion at either side of the plate B, consists of a ring 16 passing through an opening 17 provided adjacent the upper marginal edge of the plate B and through an eye 18 formed at the upper end of the straight portion 11 of the pin D; the inner diameter of the ring 16 being large enough to permit of the ready passing of the eye 18, over the ring retaining portion 19 when swinging the pin from one side of the plate to the other side thereof.

The keeper F which is adapted for holding the pin D in an operative position at either side of the plate B, and which is also capable of being swung to either side of the plate, at the lower portion thereof, consists of a substantially clevis shaped member 20 having the axially aligned eyes 21 thereof, pivotally mounted in apertures 22 provided in the plate B and disposed adjacent the lower marginal edge thereof. A bulge or offset 23 which is formed centrally of the arms of the member 20, is adapted to engage and seat in the concavity 14 of the hook portion 13 when the pin is disposed at one side of the plate as shown in Figure 5, and to engage and seat in the concavity 15 of the hook portion 13 when the pin D is disposed at the opposite side of the plate as shown in Figure 6. This bulge 23 will also aid in preventing the hook end of the pin D from moving laterally when the badge is positioned upon the apparel of the wearer.

When the pin D is disposed as illustrated in Figure 5, the material of the apparel upon which the badge is hung, will be firmly clamped between the straight end portion 11 of the pin D and one side of the plate B and when disposed as illustrated in Figure 6, the material will be firmly clamped between the crown or apex 24 of the V-shaped portion 12 and the confronting face of the plate B. It can be seen that by so clamping the material of an article of apparel or the like into frictional engagement with the plate, that the badge will be held in a set position upon the wearer or article upon which it is positioned.

It will therefore be seen that a novel and efficient badge has been provided embodying novel features for displaying indicia of different characters, and one having its attaching means so shaped as to efficiently hold the badge against displacement when being worn with either of its faces being shown.

Changes in detail may be made without departing from the spirit or scope of my invention; but,

I claim:

1. A reversible badge comprising a plate having indicia provided at each face thereof, a pin hingedly connected at one end to said

plate and swingable to a position at either face of said plate, and a keeper carried by said plate and shiftable with respect thereto, to hold said pin in either of the said positions. 65

2. A badge comprising an indicia carrying plate, a pin hingedly connected at one end to said indicia carrying plate and provided at its free end with a concaved hook portion, and a keeper pivotally carried by the indicia carrying plate having a portion thereof adapted to seat in the concavity of said hook portion for locking said pin into clamping relation with said indicia carrying plate. 70 75

3. A badge comprising an indicia carrying plate, a ring loosely carried by said plate and disposed adjacent one marginal edge thereof, a pin hingedly connected at one end to said ring and provided at its free end with a concaved hook portion, and a keeper pivotally mounted in said plate provided with an offset adapted to seat in the concavity of said hook portion for preventing lateral movement of the free end of the pin and for holding said pin in clamping relation with the indicia carrying plate. 80 85

4. A reversible badge comprising an indicia carrying plate, a pin connected at one end to said plate, a reverse curved hook portion formed at the free end of said pin, and a keeper adapted for holding the pin in an operative position at either side of said indicia carrying plate. 90 95

5. A reversible badge comprising a plate having indicia provided at each side thereof, a pin hingedly connected at one end to said plate, formed with a straight end portion, and a V-shaped portion and a keeper adapted to engage the free end of said pin for drawing said straight end portion into clamping relation with said plate when the pin is disposed at one side thereof, and the crown of said V-shaped portion into clamping relation with said plate when the pin is disposed at the opposite side of said plate. 100 105

6. A reversible badge comprising an indicia carrying plate, a pin hingedly connected at one marginal portion of said plate, adapted for swinging movement to either side of said plate, a reverse curved hook portion formed at the free end of said pin and providing oppositely disposed arcuate concavities, and a keeper pivotally mounted at one marginal edge of said plate adapted to be swung to either side of the plate and seat in the concavities of said pin for holding the pin in an operative position at either side of the plate. 110 115
